DESIGN FOR A SANITARY WASTE CAN

John F. Geibel, Buffalo, N. Y., assignor to Master Metal Products, Inc., Buffalo, N. Y., a corporation of New York

Application November 21, 1936, Serial No. 66,060

Term of patent 7 years

To all whom it may concern:

Be it known that I, John F. Geibel, a citizen of the United States, residing at Buffalo, in the county of Erie and State of New York, have invented a new, original, and ornamental Design for Sanitary Waste Cans, of which the following is a specification, reference being had to the accompanying drawing, forming a part thereof.

Figure 1 is a side elevation of the sanitary waste can embodying my design. Figure 2 is a front elevation thereof. Figure 3 is a top plan view of the same.

I claim:

The ornamental design for a sanitary waste can, substantially as shown.

JOHN F. GEIBEL.
